CLAIM

The ornamental design for a non-stackable container for cleaning golf balls, and golf equipment, as shown and described.

DESCRIPTION

FIG. 1 is an upper perspective view of a non-stackable container for cleaning golf balls, and golf equipment, showing my new design;

FIG. 2 is a top plan view thereof;

FIG. 3 is a front elevation view thereof;

mirror image thereof;

FIG. 5 is a rear elevation view thereof; and,

FIG. 6 is a bottom plan view thereof.
